(57) **CLAIM**

The ornamental design for divider for cooking utensil stand, as shown and described.

DESCRIPTION

FIG. 1 is a cross-section view of a divider for cooking utensil stand, taken along line 1-1 in FIG. 5, showing my new design, shown in environmental use;

FIG. 2 is a top perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

The broken lines in the figures illustrate the portions of the divider for cooking utensil stand and form no part of the claimed design.

The broken line showing of the cooking utensils and stand in FIG. 1 is for the purpose of illustrating environmental subject matter that forms no part of the claimed design.
